Inventor:
Thomas W. Whitacre

UNITED STATES PATENT OFFICE.

THOMAS W. WHITACRE, OF WELLSVILLE, OHIO.

DESIGN FOR AN IRREGULAR MALLET.

SPECIFICATION forming part of Design No. 14,246, dated August 28, 1883.
Application filed April 14, 1883. Term of patent 7 years.

To all whom it may concern:

Be it known that I, THOMAS W. WHITACRE, a citizen of the United States, residing at Wellsville, in the county of Columbiana and 5 State of Ohio, have invented and produced a new and original Design for Irregular Mallets, of which the following is a description.

The head is cylindrical in form, and represents in outline an obtuse angle, as is shown 10 in the drawing, and is centrally secured to the handle B in such a manner that converging planes lying in the respective faces of the mallet, when produced, will meet at the ex-

treme end of the handle. Grooves and hair-lines ornament the periphery of each end of 15 the mallet.

What I claim is—

1. The design for an irregular mallet, as described and shown.
2. The design for an irregular mallet, consisting of an angular head and the faces A, as described and shown.

THOMAS W. WHITACRE.
